(57) **CLAIM**

The ornamental design for a water spray gun, as shown and described.

DESCRIPTION

FIG. 1 is a perspective view of a water spray gun of the design.

FIG. 2 is a front elevational view of a water spray gun of the design.

FIG. 3 is a rear elevational view of a water spray gun of the design.

FIG. 4 is a left side elevational view of a water spray gun of the design.

FIG. 5 is a right side elevational view of a water spray gun of the design.

FIG. 6 is a top plan view of a water spray gun of the design; and,

FIG. 7 is a bottom plan view of a water spray gun of the design.

The broken line showing of the spray gun nozzle is included for the purpose of illustrating and forms no part of the claimed design.
